UNITED STATES PATENT OFFICE.

EDMOND R. COOK AND STEWARD L. COHOON, OF SACRAMENTO, CALIFORNIA,
ASSIGNORS OF ONE-THIRD TO THOMAS SCOTT, OF SAME PLACE.

FILTER.

SPECIFICATION forming part of Letters Patent No. 626,487, dated June 6, 1899.

Application filed August 12, 1898. Serial No. 688,415. (No model.)

To all whom it may concern:

Be it known that we, EDMOND R. COOK and STEWARD L. COHOON, citizens of the United States, residing at Sacramento, county of Sacramento, State of California, have invented an Improvement in Filters; and we hereby declare the following to be a full, clear, and exact description of the same.

Our invention relates to an improved apparatus for filtering water for domestic and other purposes.

It consists in the parts and the constructions and combinations of parts hereinafter described and claimed.

15 Figure 1 is a vertical section through the filter. Fig. 2 is a top view of the device for operating the brushes.

The object of our invention is to provide an automatically-self-cleaning filter and 20 means by which the filter is cleaned whenever water is drawn through the apparatus.

The apparatus comprises a base A, a dome B, a cylindrical outer casing C, and an inner filtering-cylinder D, which is made of any suitable 25 porous stone or filtering medium. The base and the annular plate which extends outwardly from the base of the dome B are fitted with suitable gaskets, upon which the ends of the outer casing C rest, and by means 30 of rods S, with suitable nuts, these parts are drawn together, so as to make tight joints and form a hermetically-sealed outer case. We prefer to make this outer casing C of glass, so that the interior of the apparatus 35 can be seen and the operation inspected at any time. The base-plate is provided with an inlet-opening E, which may be connected with any source of water-supply, such as the connections behind the sink or other suitable or 40 convenient place, and an outlet E², at the opposite side, with a hose-bib or service-cock of any usual or desired form.

The passage E extends to the center of the base-plate and thence opens upwardly in the 45 center, as shown at E', and the interior of the upwardly-projecting boss is screw-threaded and adapted to receive the hollow cylindrical chamber F, which has curved nozzles G projecting from opposite sides, so that through 50 these nozzles water is discharged into the interior of the apparatus.

A hollow shaft H extends upwardly from the part F, and upon this is journaled the water-wheel casing I, which in the present case is shown as consisting of a disk having a 55 downwardly-turned peripheral flange, and within this flange are the wheel-buckets I', which may be cast or otherwise formed with the disk and flange; and these buckets are of an odd number, so that the water passing out 60 through the nozzles G will impinge upon the buckets and thus rotate the wheel, and by reason of the odd number of buckets there will be no dead-center and the water will always act from at least one of the nozzles to 65 set the wheel in rotation.

Upon the opposite side of the base-plate from the inlet-nozzle E is the outlet-nozzle E², and the inner end of this connects with the interior of the base-plate and within the outer 70 casing C, so that water which is admitted through the inlet E passes up through the part F and out through the discharge-nozzles G, setting the wheel into motion and also filling the outer case around the filter D and escaping through the discharge-passage E².

The object of the rotary wheel is to carry the cleaning-brushes J. These brushes are of bristles or any suitable material fixed into a back J', which is here shown as beveled 80 upon the edges and adapted to slip into an outer casing or holder J². This allows the brushes to be removed and replaced whenever necessary. The brushes are of a length equal to the length of a filter D, and the 85 casings J² have horizontally-swiveled joints J³, which are supported upon the vertically-turnable sleeves K, and these sleeves are turnable about vertical standards K', which project upwardly from opposite sides of the 90 wheel-disk, so that the brushes may be pressed against the outer surface of the filter, and when the wheel is revolved the brushes will be moved rapidly around the filter and its surface be brushed off and cleaned. It is desirable that the brushes be held normally out 95 of contact with the filter and forced against it with any desired degree of pressure whenever the wheel is set into rotation. This is effected by connecting rocker-arms L with 100 the rotary sleeves K, and the ends of these rocker-arms are connected by loosely-jointed

links *m* with pistons or plungers *M*, which are movable within a horizontal cylinder *M'*. Springs *N* are connected with the rocker-arms *L* and with suitable attachments upon the 5 sides of the cylinder *M'*, and the tension of these springs will normally press the plungers in toward the center of the cylinder, and thus rotating the sleeves upon the standards will move the brushes away from the surface of 10 the filter.

Whenever water is admitted through the inlet *E*, it passes up and is discharged through the pipes *G* to set the wheel in rotation, as previously described, and also passes up 15 through the hollow shaft *H*, which has perforations *h* made in it, and these perforations open into the central and slightly-enlarged portion of the horizontal cylinder *M'*, so that pressure is at once applied to the plungers 20 *M*, and they are forced outwardly at the instant when the wheel commences to rotate. The plungers thus forced outwardly act through their connecting rods upon the rocker-arms *L*, and rotating the sleeves *K* 25 will force the brushes into contact with the filter-surface, and as long as the rotation of the wheel continues they will act to brush the surface of the filter. The outlet *E*² being still open, the interior of the chamber be- 30 tween the filter and the outer casing may be thoroughly washed and cleansed before the outlet is closed, and after it has been closed the water will fill the chamber between the outer casing and the filter whenever the air- 35 vent *O* is opened to allow the escape of the air from the upper part of the filter-chamber. This air-vent may be of any suitable description. We have here shown it as a simple connecting-pipe with a cock which is opened 40 at the proper time and allows the air to escape and the chamber to fill up with water. The air-cock is then closed, and the pressure of water from the inlet acts to force the water through the material of the filter to the 45 interior, and the filtered water is delivered from the interior by means of an outlet-pipe *P*, which is here shown as connected with the top of the dome *B*.

In order to conveniently obtain access to 50 the interior of the filter, we have shown the upper end abutting against the flat disk which forms the base of the dome with a suitable water-tight gasket between the two.

The lower end of the filter has an annular 55 metal cap *D'* fitted to it with a similar gasket, and a screw-rod *d* extends through the center of the filter from the bottom cap and screws into the lower end of a discharge-tube *p*, which connects with the outlet *P* of the filter. This 60 tube has perforations made in it to admit the filtered water from the interior of the dome, so that it can escape through the outlet *P*.

The plungers *M*, which operate to move the brushes, are preferably made in the form of 65 short cylinders of less diameter than the interior of the cylinder *M'* and having flanges

at each end which fit loosely within the cylinder *M'*, presenting a sufficient surface so that the outward pressure of the water will act upon them and force the brushes against 70 the filter; but the fit is loose enough so that any grit or dirt contained in the water will be allowed to escape and will not clog up the cylinders or plungers.

The pressure within the water-mains often 75 varies to a considerable extent, and in order to regulate the pressure upon the plungers and the resultant pressure of the brushes upon the filter we have shown an adjusting-valve *R*, the stem of which is screw-threaded 80 and extends up centrally through the bottom or base of the filter. The valve may be of any suitable form; but we have here shown it as a conical one and fitting into the opening at the bottom of the tubular bearing *H*, 85 upon which the wheel revolves. This valve-stem has a turning-wheel at the lower end by which it may be advanced or retracted, and the passage of the water into the hollow journal-shaft *H* is thus controlled and the pressure 90 upon the pistons *M* is regulated to suit the pressure in the mains. By this construction we are enabled to provide a filter which is automatically cleaned whenever the faucet is opened to draw water for ordinary pur- 95 poses, and when this faucet is closed the pressure within the filter-chamber will force the water through the porous filtering-cylinder and supply filtered water from the discharge-pipe thereof. 100

Having thus described our invention, what we claim as new, and desire to secure by Letters Patent, is—

1. A filter comprising an inner hollow filtering-cylinder with a discharge-opening, an 105 outer casing with supply-passages to admit the water to be filtered between itself and the filter, brushes adapted to contact with the surface of the filter and having swiveled arms whereby they adjust themselves to the surface of the cylinder upon moving about the latter, mechanism by which the brushes are moved around the filter whenever the discharge-faucet is opened. 110

2. A filter comprising an exterior case, an 115 interior hollow filtering-cylinder, supply and discharge openings connecting with the space between the outer case and the inner filter-chamber, a hollow chamber connecting with the supply-passage and having projecting 120 nozzles discharging outwardly, a water-wheel centrally journaled so that its buckets are in line with the discharge-nozzles whereby the wheel is caused to rotate when the discharge-faucet is opened, standards extending up- 125 wardly from the periphery of the wheel and brushes carried by said standards and adapt- ed to press upon the surface of the filter when the wheel is rotated.

3. A filter consisting of an outer casing, an 130 inner hollow filtering-chamber, supply and discharge openings connecting with the space

between the two, a central passage having discharge-nozzles, a centrally-journalized wheel, the buckets of which are in line with the discharge-nozzles whereby the wheel is rotated 5 when the discharge-faucet is opened, vertical standards carried upon the periphery of the wheel, brushes adapted to contact with the surface of the cylinder and having centrally-disposed swivel-arms whereby the brushes adjust 10 themselves to the surface of the filter upon moving about it.

4. A filter consisting of an outer casing, an inner hollow filter-chamber, passages through which water is admitted to and discharged 15 from the space between the two, nozzles connecting with the supply-passage, a centrally-journalized wheel, the buckets of which are in line with the nozzles whereby the wheel is rotated when water is drawn through the apparatus, vertical standards extending upwardly 20 from the periphery of the wheel, sleeves turnable loosely upon said standards, brushes adapted to contact with the surface of the filter, centrally-swiveled arms by which the 25 brushes are connected with the sleeves and a mechanism whereby the sleeves are turned so as to move the brushes into contact with the filter while in rotation.

5. In a filter of the character described, a 30 wheel which is rotated when water is drawn through the apparatus, vertical standards carried upon the wheel, sleeves turnable about said standards, brushes extending longitudinally and adapted to contact with the surface 35 of the filter, swiveled arms by which the brushes are connected with the sleeves, a cylinder with plungers movable therein, rocker-arms connected with the brush - carrying sleeves, and connections between said arms 40 and the plungers whereby the pressure of water upon the plungers acts to rotate the sleeves

and force the brushes into contact with the filter.

6. In a filter of the character described, the outer casing and axially-disposed interior filter, a rotary wheel disposed within the casing, 45 standards carried by the wheel, brushes with swivel connections turnable upon the standards whereby the brushes are moved to or from the surface of the filter, a transverse 50 cylinder having the central portion connected with the water-supply, plungers movable outwardly within the cylinder, rocker-arms connecting with the sleeves carrying the brushes, whereby the pressure of water upon the plungers acts to force the brushes into contact 55 with the filter, and springs acting to return the plungers and the rocker-arms and move the brushes out of contact with the filter when the water-pressure is cut off.

7. A filter having an exterior casing and inner filtering-cylinder, a centrally-journalized rotary wheel, brushes carried thereby and adapted to press upon the surface of the filter while in rotation, a transverse cylinder 65 with plungers movable therein, a central passage through which water is admitted to the cylinder when the cock is opened whereby the plungers are moved outwardly, connections between the plungers and the brushes 70 whereby the movement of the plunger acts to force the brushes into contact with the filter and a valve controlling the inlet-passage to the cylinder whereby the pressure may be regulated.

In witness whereof we have hereunto set our hands.
